UNITED STATES PATENT OFFICE.

WILLIAM D. REDRUP, OF HUNTINGTON, INDIANA, ASSIGNOR TO THE MAJESTIC COMPANY, OF HUNTINGTON, INDIANA, A CORPORATION OF INDIANA.

COAL CHUTE.

Application filed April 6, 1923. Serial No. 630,196.

To all whom it may concern:

Be it known that I, WILLIAM D. REDRUP, a citizen of the United States, and a resident of Huntington, in the county of Huntington and State of Indiana, have invented a new and useful Coal Chute, which invention is fully set forth in the following specification.

This invention relates particularly to grade-line coal chutes for installation in buildings with little or no foundation above the ground, such as apartments, stores and office buildings, and low set or terraced homes.

The object of the invention is the provision of a simple, improved and highly efficient chute of this character, the door of which when raised forms part of the chute hopper and becomes a shield which protects the building.

The invention is fully described in the following specification and a preferred embodiment thereof is illustrated in the accompanying drawings, in which,—

Figure 1 is a perspective view of the chute embodying the invention, with the door in open position. Fig. 2 is a side elevation thereof with the door open and with a part broken away.

Referring to the drawings, 1 designates the chute or hopper body, which, in the present instance, is rectangular in vertical cross-section and is of L-form in vertical longitudinal section with the horizontally or inwardly projecting leg thereof adapted to project inwardly through a wall opening and being open at its inner end, and with its other end provided with a top opening 2 and adapted to project upward at the outer side of the associated wall to the grade-line. The bottom of the chute body is inclined downward and inward and the outer open end of the body is provided with a frame 3 forming the opening 2.

A door 4 is hinged at its inner edge to the inner edge of the top frame 3 or at the edge thereof adjacent to the associated wall, thereby permitting the door to be swung up at the inner side of the opening 2 in protecting relation to the wall. A wing 5 is secured to the inner side of the door 4 adjacent to each side edge thereof and is of a length or size to adapt it to extend to and partially into the adjacent side portions of the opening 2 when the door is in open

position, thereby causing the door and its wings, when raised, to form part of the hopper. The outer front edges of the wings 5 are shown as being rounded to adapt them to turn down into the chute body when the door is closed, and the inner rear corner portion of each wing is notched or cut away at 6 to adapt portions of the wings to project within the horizontally projecting leg portion of the chute under the top wall 65 thereof when the door is closed. One or both of the wings 5 may be provided at its outer side with a catch 7 for engagement over the top of the frame 3 when the door is in open position to hold it in such 70 position. There is sufficient spring to the wings 5 to permit them to be sprung inward to release the engagement of the catches 7 from the frame top when it is desired to close the door.

A flanged or angle iron strip 8 is secured to the inner side of the door 4 crosswise thereof adjacent to its inner edge and an apron 9 is loosely hinged at its upper edge to the strip 8 so that when the door is in open position the apron will hang down from the door a short distance into the rear portion of the hopper opening 2 in engagement with the rear edge wall of the frame 3 and in protecting or covering relation to the crack or opening 10 between the inner lower edge of the door and the top frame. The apron 9 is of U-form so as to provide wings or flanges 11 at the ends thereof which project forward adjacent to the door wings 5 and in protecting or covering relation to the corner openings 6 of the door wings. When the door is closed the apron 9 swings down into the chute. It is evident that the apron 9 in addition to preventing 90 small pieces of coal from passing through the openings 6 and 10 when the door is opened also directs any coal or other matter striking thereagainst down over the inner rear edge of the top frame 3.

I wish it understood that my invention is not limited to any specific construction, arrangement or form of the parts, as it is capable of embodiment in numerous forms without departing from the spirit of the 95 claims.

Having thus described my invention, what I claim as new, and desire to secure by Letters Patent, is,—

1. A chute of the class described, having 110

an upwardly directed top opening, a door hinged to the top at one edge of the said opening and adapted to be raised to upright open position, wings projecting from the inner side of the door adjacent to its side edges and being of a length to project substantially into the chute opening when the door is in raised position, whereby the door and wings form a directing hopper for the chute, one of said wings being capable of inward springing movements, and means carried by said last mentioned wing and adapted to have catch engagement with the chute top to retain the door in open position and to be released by an inward springing of the wing.

2. A chute of the class described having an upwardly directed top opening at its outer end, a door hinged to the top at one edge of the opening and adapted to be raised to upright open position, and a protecting apron pivotally attached to the inner side of the door and adapted to hang downward therefrom into the rear edge portion of the opening when the door is in open position.

3. A chute of the class described having an upwardly directed top opening at its outer end, a door hinged to the chute at one edge of the opening and adapted to be raised to upright open position, wings projecting

from the inner side of the door adjacent to its side edges and adapted to extend forward from the door and down into the chute opening when the door is in raised position, and an apron hinged to the inner side of the door and adapted to hang downward therefrom into the rear edge portion of the chute opening when the door is open and having end flanges which project forward in adjacent relation to the inner sides of said wings.

4. A chute of the class described having an upwardly directed top opening in its outer end, a door hinged to the chute top at one edge of said opening and adapted to be placed in upright open position, wings projecting from the inner side of the door near the side edges thereof and extending forward therefrom and down into the respective sides of the chute opening when the door is in open position and each having a lower rear corner opening, and an apron hinged to the inner side of the door and adapted to hang down into the rear portion of the chute opening when the door is in open position and having end flanges projecting forward in covering relation to the wing openings.

In testimony whereof, I have hereunto signed my name to this specification.

WILLIAM D. REDRUP.
